UNITED STATES PATENT OFFICE.

WILLIAM H. STEDMAN, OF HARTFORD, CONNECTICUT, ASSIGNOR TO THE MERROW MACHINE COMPANY, OF HARTFORD, CONNECTICUT, A CORPORATION OF CONNECTICUT.

THREAD-GUIDE FOR SEWING-MACHINES.

SPECIFICATION forming part of Letters Patent No. 732,458, dated June 30, 1903.

Application filed March 18, 1902. Serial No. 98,808. (No model.)

To all whom it may concern:

Be it known that I, WILLIAM H. STEDMAN, residing in the city of Hartford, county of Hartford, State of Connecticut, have invented certain new and useful Improvements in Thread-Guides for Sewing-Machines; and I do hereby declare the following to be a full, clear, and exact description of the same, reference being had to the accompanying drawings, forming a part of this specification, and to the figures of reference marked thereon.

This invention relates particularly to thread-guides and those elements or parts of a sewing-machine immediately associated therewith, the invention being especially applicable to a type of machine similar to that shown and described in a former application for United States Letters Patent filed by me December 18, 1901, and bearing Serial No. 86,440.

The object of the invention is to provide improved means for conducting a thread to a movable looper having a thread-carrying eye, to facilitate the introduction of thread through the eye of the looper, and to specially construct and arrange various parts of the machine which are intimately associated with the said looper and guides for its thread.

In the drawings, Figure 1 is an end elevation of the needle-plate, thread-guides, looper, and feed-dog constructed in accordance with this invention, this view also showing certain other elements or parts, including the presser-foot and in dotted lines a portion of the outline of the machine-frame. Fig. 2 is a front elevation of the parts shown in Fig. 1. Fig. 3 is a plan view of the parts shown in Figs. 1 and 2 with the exception of the presser-foot. Fig. 4 is a rear elevation of the needle-plate. Fig. 5 is a front elevation of the operative end of the looper.

Like reference-figures refer to the same parts in the several figures of the drawings.

Referring to the drawings, the number 10 denotes the machine-frame, 11 a support secured thereto for the needle-plate, 12 the needle-plate, 13 the feed-carrier, 14 the feed-dog, and 15 the presser-foot adapted to coöperate with the said feed-dog, said elements being

assembled in the machine and relatively to 50 each other in the usual manner.

The number 16 denotes a looper adapted to travel to and fro beneath the needle-plate 12. The looper 16 is "eye-pointed," and the eye denoted by the reference-number 16^a is 55 adapted to receive the thread 17.

The feed-dog 14 is cut away at 14^a, as usual in this class of machines, to permit the looper 16 to travel therethrough. The operative or toothed face of the feed-dog is thus divided 60 into front and rear portions 14^b 14^c, of which the former in this present instance is subdivided by a groove 14^d, Fig. 2, extending longitudinally of the feed-dog or at right angles to the length of the machine. Two 65 distinct feeding-surfaces are thus provided at the forward end of the feed-dog, which feeding-surfaces project through openings 12^a 12^b in the needle-plate 12, while a third opening 12^c in the needle-plate receives the rear 70 portion 14^c of the feed-dog. Any other suitable known form of feed-dog may, however, be used.

Located on the under side of the needle-plate 12, between the openings 12^a 12^b, is a rib 75 or block 12^d, formed integrally with the plate 12 or secured thereto and extending from a point near the forward end of the said needle-plate to a point adjacent the path in which the eye-pointed end of the looper 16 travels. This block 12^d is provided with a thread-passage 12^e therethrough, as hereinafter described, and the groove 14^d of the feed-dog 14 constitutes a space for the accommodation of the block or rib, as shown in Fig. 2. The 80 thread-passage 12^e extends throughout the length of the block or rib 12^d and preferably in a line slightly diagonal to the line of the feed, but may be parallel therewith, as circumstances may demand.

The needle-plate 12 is preferably not mounted directly upon its support 11; but there is interposed between the two an element 18, known as a "shim." It is held in place by screws 19, passing therethrough and also serving to secure the needle-plate 12 to the support 11. The shim 18 is provided with a groove 18^a to direct the thread 17 in a well-

rounded course to the before-mentioned thread-passage 12^e, the thread usually rendering to the passage in a direction nearly at right angles thereto, as shown in Fig. 3, and to protect the thread the shim is further provided with an overhanging portion 18^b. While the needle-plate 12 and the shim 18 are shown and described as two separate elements, the same are so constructed for convenience of manufacture only, it being obvious that the shim is practically a part of the needle-plate and may be integral therewith. It should also be noted that while the passage 12^e is shown as being located in a rib 15 formed on the needle-plate proper, which construction shows the preferred form of my invention, conditions might exist occasioned by a needle-plate of peculiar shape in which it might be preferable to locate the passage directly in the needle-plate proper, or the said passage could be located in an integral extension of the shim.

In "threading up" the looper 16 the thread 17 is passed through the shim-groove 18^a and the thread-passage 12^e and threaded through the looper-eye 16^a, thus making a convenient and direct route for the thread from the exterior of the machine through the eye of the looper. The rear end of the thread-passage 30 12^e is closely in alignment and in proximity with the eye 16^a of the looper 16 when the latter is at the extreme outward limit of its travel, so that the thread 17 is supported and guided directly to and through the eye of the 35 looper, thereby greatly facilitating the threading operation, this arrangement being especially convenient when a "threading-wire" is used to introduce the thread.

To enable the looper 16 to travel beneath the needle-plate 12 in an elevated position, the said plate is preferably provided in its under face with a groove 12^f, extending at right angles to the direction of the line of feed and the block or rib 12^d, the groove 12^f being 45 adapted to receive the eye-pointed portion of the looper in the manner best shown in Figs. 1 and 2. The rearward end of the block or rib 12^d preferably extends somewhat beyond the adjacent side of the groove 12^f and into proximity to the path in which the eye-pointed end 50 of the looper travels for the purpose already explained.

Having thus described my invention, what I claim as new, and desire to secure by Letters 55 Patent, is—

1. In a sewing-machine and in combination, a needle-plate, a thread-carrying looper provided with an eye reciprocating beneath the needle-plate, a guide for the looper-thread arranged beneath the needle-plate in front of 60 and in proximity to the line of travel of the looper whereby the looper-thread is held in position to be passed through the eye of the looper in threading the same and is guided and rendered to the eye of the looper during 65 its reciprocations, substantially as described.

2. In combination, a needle-plate having a rib on its under face with a thread-passage therethrough, a support for the needle-plate, an element intermediate the needle-plate and support having a groove therein leading from its front edge to the said thread-passage through which groove a thread may render freely to the passage from a direction at an angle thereto, substantially as described. 75

3. In combination, a needle-plate having a rib on its under face with a thread-passage therethrough, a support for the needle-plate, an element intermediate the needle-plate and support having a groove therein leading from 80 its front edge to the thread-passage through which groove a thread may freely render to the said passage from a point at an angle thereto and the said intermediate element being further provided with a projecting portion at its front edge for the protection of the thread, substantially as described.

4. In combination, a needle-plate having feed-dog openings therein and a rib on its lower face with a thread-passage therethrough 90 located between two of the said openings, a reciprocating looper beneath the needle-plate, a feed-dog having a portion of its feeding-surface grooved to clear the said rib, substantially as described. 95

5. In combination, a needle-plate having a rib on its under face with a thread-passage therethrough, a looper adapted to travel beneath the needle-plate in a path near the end of the thread-passage and a feed-dog cut 100 away to permit of the travel of the looper and having its forward end grooved to clear the said rib and having an opening therethrough to permit of the travel of the looper, substantially as described.

WILLIAM H. STEDMAN.
